FINGER RING

Tony E. Foster, Indianapolis, Ind., assignor to
Herff-Jones Co., Indianapolis, Ind.

Application March 13, 1937, Serial No. 130,738

1 Claim. (Cl. 63—15)

This invention relates to a method of forming a finger ring and has for its primary object the forming of a ring which will have a massive appearance accompanied by light weight and at the same time permitting the forming of the ring entirely out of a single metal without having to employ less precious metals or the like for fillers. A still further primary object of the invention is to form a ring of the above indicated nature from a number of parts which may be assembled and formed into an integral ring without having exposed edges of the juncture of different metals.

These and other objects and advantages of the invention will become apparent to those versed in the art in the following description of one particular embodiment of the invention as illustrated more or less diagrammatically in the accompanying drawing, in which

20 Fig. 1 is a top view in perspective of a finger band blank;

Fig. 2, a similar view of a slightly modified form of the blank;

Fig. 3, the blank formed into a ring;

25 Fig. 4, a view in perspective of a side plate here shown as plain in design;

Fig. 5, a top view in perspective of a mounting crown;

Fig. 6, a top view in perspective of a disassembled relation of the ring;

Fig. 7, a top perspective view of a completed ring; and

Fig. 8, a section on an enlarged scale through the completed ring at one side of the center.

30 Like characters of reference indicate like parts throughout the several views in the drawing.

The first step is to form a finger band blank generally designated by the numeral 10 to have a central portion formed with a recess or depression 11 bounded on the two lateral sides by the shoulders 12 and 13. In that form of the band shown in Fig. 1, there is left a raised portion extending laterally across the depressed area in the form of a bar 14. This bar may be omitted in many cases as indicated in the form shown in Fig. 2. The use of the bar 14 is to reinforce the under wall of the depressed area or zone or to be utilized as a means for securing stones or the like in place in the finished ring.

50 The finger band 10 formed as above indicated is then further formed to bring it into the finger ring shape as indicated in Fig. 3 where the two ends of the blank have been united at some position such as at A. In curving the blank around to this ring shape, the under wall 15 of the de-

pressed zone 11 is likewise curved and in so doing, the extreme upper areas of the shoulders 12 and 13 are brought into a flattened condition, both coming then into the same plane. In order to accomplish this result, these shoulders 12 and 13 have their upper faces originally concave as indicated in Figs. 1 and 2.

Any suitable mounting crown is then formed to be carried on these upper flattened faces of the shoulders 12 and 13. In the form herein shown, Fig. 5, the crown 16 is generally oblong in shape and proportioned to have the upper sides of its ends rest respectively on these upper faces of the shoulders 12 and 13 to have the ends of the crown coincide with the outer margins of these shoulders. Of course any desired ornamentation may be employed about the crown piece 16 but for the sake of clearness, the crown is herein shown as having plain or outer walls devoid of ornamentation.

20 A pair of side plates 17 and 18 of the general configuration as shown in Fig. 4 is formed so as to cover over those portions of the depressed zone 11 exposed between the sides of the crown 16 and the longitudinal ends of that zone. The crown 16 and the side plates 17 and 18 are secured to the finger band proper and one to the other in any of the well known methods such as by soldering or fusing.

25 The crown 16 may be formed for either an all metal or a stone mounting, the form herein shown being that for a stone mounting. In this form, a stone 19 is shown as being mounted on the crown 16 and is further shown as having a metal ornament 20 mounted on the outer side of the stone 19 to have a rivet 21 extending through the stone and down through the wall 15. As indicated in Fig. 8, the reinforcing bar 14 may be employed in this type of mounting to advantage for reinforcing the wall 15 and also provide for suitable thickness for retaining the headed end of the rivet 21. Further, as indicated in Fig. 8, it is to be noted that while the ring externally presents a large and massive appearance, this appearance is not secured at the disadvantage of added weight. Instead the space below the crown piece 16 bounded by the plates 17 and 18 and the under wall 15 is left hollow and is not filled in. Furthermore it is to be noted that the entire finger band which would contact the finger of the wearer is made of a single piece of metal without inlays or fillers exposed or otherwise and consequently there is but one color of metal exposed both on the inner side of the band and on its edges.

While I have herein shown and described my invention in the one particular form, it is obvious that structural variations may be employed without departing from the spirit of the invention and I, therefore, do not desire to be limited to that precise form beyond the limitations as may be imposed by the following claim.

I claim:

A finger ring comprising an endless one piece band with a recess formed therein on its outer side and bounded by a surrounding shoulder having central portions thereof on opposite edges of the band increased in height to define a

crown seat, and said band having a bar extending centrally across such recess between said raised central portions of the shoulder and upstanding from the bottom of the recess, a mounting crown secured to and resting by its ends on said central portions of the shoulder across and above said recess, side plates covering over and enclosing the portions of said recess on either side of said crown, resting on said shoulder and in abutment with the sides of said crown, a setting on the mounting crown and means comprising a rivet securing the setting to said bar. 5 10
